UNITED STATES PATENT OFFICE.

GEORGE H. GILMAN, OF CLAREMONT, NEW HAMPSHIRE, ASSIGNOR TO SULLIVAN MACHINERY COMPANY, OF CLAREMONT, NEW HAMPSHIRE, A CORPORATION OF MAINE.

FLUID-PRESSURE TOOL.

No. 853,921.

Specification of Letters Patent.

Patented May 14, 1907.

Application filed December 19, 1905. Serial No. 292,418.

To all whom it may concern:

Be it known that I, GEORGE H. GILMAN, a citizen of the United States, residing at Claremont, in the county of Sullivan and State of New Hampshire, have invented an Improvement 5 in Fluid-Pressure Tools, of which the following description, in connection with the accompanying drawings, is a specification, like letters on the drawings representing like parts.

My invention relates to fluid pressure engines, such as are operated by compressed air or other elastic fluid, and is more particularly though not exclusively concerned with the 15 provision of a new and improved pneumatic hammer.

My invention will be best understood by reference to the following specification when taken in connection with the accompanying 20 illustration of one specific embodiment thereof submitted for illustrative purposes, while its scope will be more particularly pointed out in the appended claims.

In the drawings, Figure 1 is a longitudinal 25 central section taken through a pneumatic hammer embodying one form of my invention and showing the controlling valve and the piston in one position; Fig. 2 is a similar sectional view showing the valve and piston 30 in different positions; Fig. 3 is a section on the line 3—3, Fig. 1; Fig. 4 is a section on the line 4—4 in Fig. 1; Fig. 5 is an end view on an enlarged scale of the transverse controlling valve employed in the hammer illustrated in Fig. 1; and, Fig. 6 is a side elevation of the same.

Referring to the drawings and to the specific embodiment of my invention there illustrated, the cylinder *a* is threaded into 40 the chambered head *b*; the cylindrical valve block *c* acting as a closure for that end of the cylinder which is entered within the chamber. The cylinder and valve block are maintained in the necessary alinement required for the 45 registration of their connecting passages by means of dowel pins (not shown). Slidably fitted over the head end of the casing is the grasping handle *e*, secured thereto and guided thereon by the hollow threaded stud *f*, which 50 latter passes through the slot *e'* in the base of the handle, the handle thereby having a limited movement toward and away from the casing.

The head or casing is provided with a constant pressure chamber *g*, facing the valve block to which chamber, when the tool is in use, air or other elastic fluid is constantly supplied through the inlet *f'* within the hollow stud and thence through the supply passage *f''*.

For control of the air admission to the pressure chamber there is provided a longitudinally arranged throttle valve lying across and controlling the passage *f''* and comprising the piston heads *h* and *h'* of equal diameter and separated by the neck or contracted portion *h''*. The piston portion *h'* works in a cylindrical cup or pocket suitably formed in the head, to the bottom of which leads the auxiliary pressure duct *i*, the lower end of the piston head *h'* being thereby exposed to a constantly acting pressure. When the tool is pressed against its work the hand pressure upon the sliding handle acts against the head *h* of the throttle valve and forces the latter 70 into the position shown with the contracted portion lying across the supply passage and permitting free passage therethrough of the supplied pressure. When the operator withdraws the tool from the work and relieves the 75 pressure of his hand against the grasping handle, the constantly acting fluid pressure upon the piston head *h'* at the forward end of the throttle valve forces the latter back against the handle and pushes the handle 80 outward upon the casing. The valve follows the handle in its movement until the latter is brought to rest against the stud *f*, this movement of the valve being sufficient 85 to bring the valve piston head *h'* across the supply passage in position to close the same.

The cylindrical valve block *c* has a transversely arranged valve chamber within which works the differential valve *d*, employed to control the piston movement. The valve 95 chamber consists of a diametrical passage having a reduced end portion *d'*, to which live pressure is constantly admitted from the constant pressure chamber *g*, through the pressure supply duct *d''*. The valve chamber 100 is closed at each end by the sleeve *s*, which embraces the entire valve block.

Live pressure is admitted from the constant pressure chamber *g*, to the valve chamber, through the unobstructed admission passage *g'*, the latter having a rectangular cross

section of ample area and from the valve chamber to the head end of the cylinder through the cylinder passage g^2 of similar shape and size. These two passages are in 5 rectilinear alinement when the valve is positioned as shown in Fig. 1, for the direct and unobstructed passage of the pressure from the constant pressure chamber to the cylinder, this admission taking place about the 10 contracted neck portion d^3 of the valve, which portion is formed intermediate the reduced end portion d^4 and the relatively larger end portion d^5 , the former working within the contracted chamber d^6 , and the latter in the 15 opposite and larger end of the valve chamber.

During the forward movement of the piston, the valve is held in the position shown in Fig. 1, by the pressure constantly acting upon the reduced end d^4 , during which time 20 active pressure is freely admitted to the head end of the cylinder to drive the piston forward and deliver the blow upon the tool shank t , the latter being held within the usual sleeve or bushing t' .

25 During the forward movement of the piston the controlling valve is reversed by the admission of fluid pressure to the larger end of the valve chamber, this acting against the larger valve end to overbalance the pressure

30 upon the smaller end and move the valve to the position shown in Fig. 2. This valve reversing pressure is received through a longitudinal intermittent pressure port j , which, opening 35 intermittently into the cylinder at j' , and extending lengthwise through the cylinder walls and the valve block, connects the interior of the cylinder with the larger end of the valve chamber. This intermittent pressure port is intermittently placed in communication 40 through piston movement with a constant pressure port k , which latter, extending longitudinally from the constant pressure chamber g through the valve block and the cylinder walls, opens within the cylinder at k' .

45 The piston has the main or larger portion l working within the main cylinder chamber and the reduced forward portion l' , adapted to enter the contracted cylinder walls a' on the forward piston movement to close the 50 cylinder to the tool space beyond. The main cylinder portion is provided with a pair of separated circumferential grooves l^2 connected by the several longitudinal and exterior grooves or depressions l^3 . Formed upon

55 the interior walls of the cylinder and alining with the openings j' and k' , respectively, are the interior peripheral grooves j^2 and k^2 . When on the forward piston movement the forward piston groove l^2 crosses the cylinder

60 groove j^2 , the intermittent pressure port j is immediately placed in communication with a constant pressure port k , through the system of grooved connecting piston passages, and the pressure acting upon the enlarged valve 65 end instantly moves the same into the re-

verse position shown in Fig. 2. In this reversed position of the valve the cylinder passage g^2 is cut off from the admission passage g' by the interposition of the enlarged valve portion and placed in communication with the exhaust through the opening or chamber d^6 formed upon the exterior of the valve which opening connects the cylinder with the exhaust passage m the latter leading into the annular space surrounding the valve block 75 and communicating with the exterior through the radial exhaust passages m' . At the same time the admission passage g' is placed in communication with the tool end pressure port n by means of the interiorly formed 80 valve passage d^7 . The tool end pressure port n communicates with the interior of the cylinder at the forward end thereof and, on reversal of the valve, acts to admit pressure from the constant pressure chamber g and 85 the interior valve passage d^7 to the tool end of the cylinder, where acting upon the reduced piston area between the enlarged and contracted piston portion, it is effective in causing the instantaneous return of the piston 90 after its blow has been delivered, although insufficient materially to reduce the piston momentum before the blow is struck.

On its return movement the piston cuts off pressure from the larger area of the differential valve as soon as the forward piston groove l^2 crosses or passes the cylinder groove j^2 . Further reverse movement of the piston withdraws the reduced portion l' from the contracted cylinder walls, placing the tool 100 end of the cylinder in communication with the tool space and the tool end exhaust passage o . This is accompanied or soon followed by the uncovering of the cylinder groove j^2 through further retraction of the piston, this 105 acting to exhaust the pressure back of the enlarged end of the valve and cause the return of the same under the constantly acting pressure to the position shown in Fig. 1. In this position pressure is again admitted to the 110 head end of the cylinder while cut off from the tool end thereof, the air at the tool end being exhausted through the exhaust opening o . The momentum of the piston being overcome by the admission of air at the head 115 end thereof, piston movement is reversed and it proceeds on its forward stroke, as before described.

To relieve the valve of any pressure which might collect at the shoulder formed between the contracted and enlarged portions and thus retard the valve movement, an exhaust or leakage passage p is formed laterally in the valve block c , and, opening into the annular exhaust chamber, permits the escape 125 of any pressure which might retard the valve.

The correct alinement of the connecting passages in the sleeve and the valve block is maintained by means of the threaded pi 130

and the proper alignment of the valve within the block by means of the pin r' .

It will be observed that the admission passage g' from the constant pressure chamber to the valve chamber and the cylinder passage g^2 from the valve chamber to the cylinder, are in direct alignment, affording thereby a direct path for the admitted pressure and avoiding that diffusion of the fluid pressure which is usually occasioned by its passage about corners and through circuitous routes. The area of these passages is preferably of ample amount and the contracted neck portion d^3 of the valve is preferably though not necessarily so reduced as to occupy but a small portion of the direct admission passage formed through the valve chamber and the valve block, thereby permitting a large part of the admitted pressure to pass on either side of it with practically no obstruction whatever.

The provision of grooved passageways in or upon the piston permits the effective intermittent admission of pressure to the larger end of the valve chamber without disadvantageously reducing the bearing surface of the piston.

While I have illustrated and disclosed one embodiment of my invention for illustrative purposes, it is to be understood that the same is not limited to the details, form or relative arrangement of the parts disclosed, but that extensive modifications thereof may be made without departing from the spirit of my invention.

Claim.

1. A differential fluid pressure engine having a differential piston and a transverse differential piston controlling valve, the latter provided with closed ends, an intermediate contracted neck portion about which pressure admission to one end of the cylinder takes place when the valve is suitably positioned, a constant pressure supply passage in lateral communication with said neck and an interior passage through which pressure admission to the opposite cylinder end takes place when the valve is oppositely positioned.

2. A direct fluid pressure engine having a differential piston and a transverse differential piston controlling valve, the latter provided with closed ends, an intermediate contracted neck portion about which pressure admission to the cylinder takes place when the valve is suitably positioned, a constant pressure supply passage in lateral communication with said neck and an exterior chambered portion through which exhaust from the cylinder takes place when the valve is oppositely positioned and an interior passage through which pressure admission to the opposite cylinder end takes place when the valve is oppositely positioned.

3. A fluid pressure engine having a differential piston, and a transverse differential

piston controlling valve, the latter being provided with a contracted neck portion about which pressure admission to one end of the cylinder takes place when the valve is suitably positioned, a constant pressure supply passage in lateral communication with said neck, an exterior chambered portion through which exhaust from said cylinder end takes place when the valve is oppositely positioned, and an interior passage through which pressure admission to the opposite cylinder end also takes place when the valve is oppositely positioned.

4. A fluid pressure engine having a cylinder, a differential piston, a differential piston-controlling valve provided with closed ends, and an interior passage through which pressure admission takes place to one end of the cylinder and a passage for admitting pressure to the opposite end of the cylinder, a passage leading from the pressure supply and opening into the cylinder; a second passage leading from the cylinder to one end of said valve, separated circumferential grooves upon the piston and connecting passages between said grooves whereby when the piston is suitably positioned the said two passages are placed in communication and pressure admitted to one end of the valve.

5. A fluid pressure engine having a cylinder, a cylindrical valve block at the rear of said cylinder and forming a closure for the same, a valve transversely mounted in said block and of substantially the longitudinal extent of said block a sleeve embracing the block and a chambered head inclosing said valve, block and sleeve and having interior threads adapted to engage with similar exterior threads upon said cylinder which clamps the valve block and said sleeve within the chamber of said head and between the same and the cylinder end.

6. A fluid pressure engine having a cylinder, a chambered head secured thereto, a cylindrical valve block within the chambered head and forming an end closure for the cylinder, a valve transversely arranged in said block and a separate sleeve embracing the said block and within said chambered head and of substantially the longitudinal extent of said block.

7. A fluid pressure engine comprising a cylinder and a piston, a transversely arranged differential valve having closed ends, an intermediate passage by which pressure admission to one end of the cylinder takes place when the valve is suitably positioned and an interior passage through which pressure admission takes place to the opposite cylinder end when the valve is oppositely positioned, said valve having an area exposed to constant pressure and a larger area exposed to intermittent pressure, means for admitting pressure to the larger area to reverse the valve on forward piston movement,

means acting through reversal of the valve for admitting pressure to the tool end of the piston, a reduced piston portion slidable within contracted cylinder walls at the forward end of the cylinder and an exhaust passage connecting the tool space in front of said contracted cylinder portion, the withdrawal of said reduced piston portion from the contracted cylinder walls permitting pressure to exhaust from the tool end of said cylinder and from the larger area of the valve.

8. A fluid pressure engine having a cylinder, a differential piston, a transversely arranged differential valve having closed ends, an intermediate passage by which pressure admission to one end of the cylinder takes place when the valve is suitably positioned and an interior passage through which pressure admission takes place to the opposite cylinder end when the valve is oppositely positioned, said valve having an area exposed to constant pressure and a larger area exposed to intermittent pressure, ports controlled by said valve for admitting pressure alternately to opposite sides of the piston, and an exhaust passage leading from within the cylinder near the forward end thereof and adapted to be uncovered by the rearward movement of the piston, said rearward movement acting thereby both to exhaust the pressure from the tool end of the cylinder and from the larger area of the valve.

9. A fluid pressure engine comprising a cylinder and a piston, a transversely arranged differential valve having closed ends, an intermediate passage by which pressure admission to one end of the cylinder takes place when the valve is suitably positioned and an interior passage through which pressure admission takes place to the opposite cylinder end when the valve is oppositely positioned, said valve having an area exposed to constant pressure and a larger area exposed to intermittent pressure, ports controlled by said valve for admitting pressure alternately to opposite sides of the piston, and an exhaust passage leading from within the cylinder near the forward end thereof and adapted to be uncovered by the rearward movement of the piston, said rearward movement acting thereby both to exhaust the pressure from the tool end of the cylinder and from the larger area of the valve.

10. A fluid pressure engine having a cylinder, a differential piston, a transversely arranged differential valve having closed ends, an intermediate passage by which pressure admission to one end of the cylinder takes place when the valve is suitably positioned and an interior passage through which pressure admission takes place to the opposite cylinder end when the valve is oppositely positioned, said valve having an area exposed to constant pressure and a larger area exposed to intermittent pressure, means for admitting pressure to the larger end thereof to reverse the valve on forward movement of the piston, means acting through reversal of the valve for admitting pressure to the tool end of the piston, a reduced piston portion slidable within contracted cylinder walls at the forward end of the cylinder, the withdrawal of said reduced piston portion from the contracted cylinder walls permitting pressure to exhaust from the tool end of said cylinder and from the larger area of the valve.

sure to exhaust from the tool end of said cylinder.

9. A fluid pressure engine comprising a cylinder and a piston, a transversely arranged differential valve having closed ends, an intermediate passage by which pressure admission to one end of the cylinder takes place when the valve is suitably positioned and an interior passage through which pressure admission takes place to the opposite cylinder end when the valve is oppositely positioned, said valve having an area exposed to constant pressure and a larger area exposed to intermittent pressure, ports controlled by said valve for admitting pressure alternately to opposite sides of the piston, and an exhaust passage leading from within the cylinder near the forward end thereof and adapted to be uncovered by the rearward movement of the piston, said rearward movement acting thereby both to exhaust the pressure from the tool end of the cylinder and from the larger area of the valve.

In testimony whereof, I have signed my name to this specification, in the presence of subscribing witnesses.
